Attorney.

UNITED STATES PATENT OFFICE.

LOUISA B. SADDINE, OF HOT SPRINGS, ARKANSAS.

WATER-COOLER.

SPECIFICATION forming part of Letters Patent No. 498,817, dated June 6, 1893.

Application filed November 8, 1892. Serial No. 451,345. (No model.)

To all whom it may concern:

Be it known that I, LOUISA B. SADDINE, a citizen of the United States, residing at Hot Springs, in the county of Garland and State of Arkansas, have invented certain new and useful Improvements in Water-Coolers; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention is a water cooler, and consists in the novel construction and arrangement of its parts.

Figure 1 is an elevation of my invention. Fig. 2 is a vertical sectional view, and Fig. 3 is a perspective view of the ice-chest seated on the base.

The particular purpose of my cooler is to so have the ice placed in the center of the cooler that the water may be quickly cooled and kept cool and at the same time not come in contact with the ice.

To this end my invention is constructed as follows:

A, is the tank, a, is the faucet, a', are the handles, and B, is the cover. Said tank is a non-conductor and consists of the outside tank A, and inside can C, which are united at the bottom and top by annular pieces c. Said inside can is provided on its inner face, near its mouth with annular projection c'; on said annular projection rests a strainer. Said inside can is provided with an interior truncated cone-shaped bottom D, the bottom edge of which is united with the bottom edge of the interior can C, in such a manner that said can C, is water-tight, the water surrounding said bottom. I provide a base E, for the tank A, to sit on. In the center and on the upper face of said cooler, is secured a truncated cone-shaped ice-holder F, that exactly fits on the inside of the truncated cone-shaped bottom D. Said truncated cone-shaped ice-holder F, is provided with a partition f, leaving a considerable space between said partition and base E,

the spaces between the tank and inside can is filled with charcoal and saw dust, or other non conductors, and the space between the partition f, and the base E, is also filled with saw dust and charcoal or other non conductors. The neck of the faucet passes through both tank and can, so as to reach the water.

In manipulating my water cooler the ice chest F, is first filled with ice, the can is then set down over said ice-holder onto the base E. The strainer c', is then put in place and the water poured into the cooler through the strainer and then the cover B, is put on. Said cover B, may also be provided with a pocket just above the strainer to be packed with a non conductor if desired.

It will be seen, I think, that my cooler is constructed differently from any now in use. I have no splashing of water when the ice is put in. It is quickly and without trouble packed into the ice chest, and when the tank is set down over the chest, the cold quickly passes through the metal and chills the water. With this arrangement pure water may be used and cooled without coming in contact with the ice. Recent scientific discovery has developed the fact that ice contains many germs of disease and for that reason it is not always safe to come in contact with the water we use.

Having described my invention, what I claim as new, and desire to secure by Letters Patent, is—

A water-cooler having its base portion provided with a truncated cone-shaped ice-holder F, open at the top, and a removable water-holder having its base of a shape corresponding to the ice-holder, so that the water-holder may be placed over the refrigerant to cool the water, substantially as shown and described and for the purposes set forth.

In testimony whereof I affix my signature in presence of two witnesses.

LOUISA B. SADDINE.
